UNITED STATES PATENT OFFICE.

FRITZ GIRARD, OF HANAU-ON-THE-MAIN, GERMANY.

REFLECTOR FOR QUARTZ LAMPS.

Application filed August 24, 1921, Serial No. 494,983, and in Germany February 2, 1919.

(GRANTED UNDER THE PROVISIONS OF THE ACT OF MARCH 3, 1921, 41 STAT. L., 1313.)

My invention relates to irradiation quartz lamps for medical purposes and more especially to lamps having a parabolic cylindrical metal reflector. Such lamps heretofore involved the drawback that the utilization of the light was rather imperfect owing to insufficient reflection by the lamp casting serving mainly as a light screen. It is an object of my invention to provide a lamp in which the entire radiation of a quartz lamp for medical purposes is thoroughly utilized in a comparatively narrow bundle of light rays which however, for the particular purpose is large enough.

Up till now the use of a metal reflector in the form of a parabolic cylinder on account of the dimensions of the lamp at the pole vessels required reflectors of comparatively great focal length, which had an opening of unsuitably great width and great dispersion, that means a very large bundle of light of limited intensity.

According to my invention, now, I utilize only that part of a parabolic cylindrical reflector, the curvature of which is flat, while the more strongly curved portion at the vertex of the parabola by which it is formed, is replaced by a small reflector of quartz glass, porcelain or some other suitable refractory material, which is disposed nearer to the source of light and is also shaped like a parabolic cylinder. This reflector of quartz glass, which can be placed very close to the arc, can have a very short focal length and although being comparatively small (as required on account of the costs of quartz glass) is capable of taking up the light which heretofore was radiated to the rear and practically not utilized at all up to a half circle and somewhat more and reflected to the front to be utilized then.

I am aware that it is not new per se to provide lamps with a reflector in two parts, the outer part being made of metal. Such reflectors are well known in head lights for motor cars, but here they serve a different purpose and besides do not fulfill the condition of the outer part having a great and the inner as small a focal length as possible. Moreover the inner part in the old reflectors is not made of quartz glass or the like, a feature, which allows to reduce the emitting opening of the reflector while the

source of light is surrounded to a large extent by the inner reflector.

A special modification of the new reflector is characterized by the parabolic central portion consisting of quartz being subdivided into two portions with an air gap between them of a width equal to the thickness of the arc, that is, about 4 mm. Although the reflection at the vertex is thereby abolished, this gap does not in any appreciable extent detract from the effect, as the light reflected at this point is for the greater part unable to pass through the arc. On the other hand, this air gap is of particular value for the cooling of the quartz lamp and the reflector itself. The gaps formed between the small and the large reflector are also advantageous on account of the comparatively small surfaces which are available for the abduction of heat. They increase the circulation of air and consequently the abduction of heat, which is indispensable for the successful operation of quartz lamps.

Preferably, the new reflector consisting of several parts is so designed, that its outer part is formed of two plane metal mirrors. This substitution can be made without difficulty as the portions used have a flat curvature.

By constructing the quartz reflector in two parts, it is possible to substitute its parabolic halves by approximate halves of a cylinder. This does not affect the efficiency to any appreciable extent but greatly facilitates manufacture.

In the drawings affixed to this specification and forming part thereof, a lamp embodying my invention is illustrated diagrammatically by way of example. In the drawings—

Fig. 1 is a cross section and

Fig. 2 a longitudinal section of my improved reflector.

Fig. 3 is a side view of the device, and

Fig. 4 is a like view showing the reflector in tilted position.

a is a quartz lamp, *b* the inner part, which consists of quartz, and *c* the outer metallic part of the reflector. The inner part has the focal length *f*, the outer part the focal length *g* as follows from the parabola shown in dotted lines. For comparison, a reflector *d* is shown in dotted lines in order to indicate the radiation opening required by a

reflector made exclusively of metal, the focal length h of which were adapted to the pole vessel dimensions of the quartz lamp. In the reflector e , having the focal length i (also shown in dotted lines) the clearance for tilting the quartz lamp is considered, if the lamp should be adapted to be tilted within the reflector in order to ignite it. This tilting of the lamp can be effected according to my invention together with the reflector which, owing to the small dimensions and the limited weight of the reflector has no detrimental consequences for the quartz lamp.

This is shown in Figs. 3 and 4, the metallic reflector e being pivoted at m to the free end of a screw spindle k provided with a crank handle l and extending through a nut o pivoted to the support p , to which the reflector is pivoted at n and which is capable of turning about a horizontal spindle q housed in the cross arm of the standard, thereby allowing the lamp to be tilted in a vertical plane for purposes of ignition. Fig. 3 shows the reflector in the position for horizontal projection, the position for vertical projection being shown in dotted lines. Fig. 4 illustrates an intermediate position.

A further advantage of the new reflector, consists in the fact, that it can be rotated about the quartz lamp remaining in horizontal position about an axis which is disposed in the centre of a lighting tube. The light of the quartz lamp concentrated by the reflector can consequently be radiated upwards, downwards and laterally as required.

I wish it to be understood that I do not desire to be limited to the exact details of construction shown and described, for obvious modifications will occur to a person skilled in the art.

I claim:

1. Irradiating device comprising a reflector of refractory material, a quartz lamp near the focus of said refractory reflector and a second reflector, said refractory reflector being arranged to reflect the rearwardly emitted rays, said second reflector the forwards emitted rays of said lamp, said second reflector having a greater focal length than said refractory reflector.

2. Irradiating device comprising a reflector of refractory material, a quartz lamp

near the focus of said refractory reflector and a second reflector, said refractory reflector being made of quartz glass and arranged to reflect the rearwardly emitted rays, said second reflector the forwards emitted rays of said lamp, said second reflector having a greater focal length than said refractory reflector.

3. Irradiating device comprising a reflector of refractory material and formed in two parts separated by a gap, a quartz lamp near the focus of said refractory reflector and a second reflector, said refractory reflector being arranged to reflect the rearwardly emitted rays, said second reflector the forwards emitted rays of said lamp, said second reflector having a greater focal length than said refractory reflector.

4. Irradiating device comprising a reflector of refractory material, a quartz lamp near the focus of said refractory reflector and a second reflector formed of two substantially flat portions, said refractory reflector being arranged to reflect the rearwardly emitted rays, said second reflector the forwards emitted rays of said lamp, said second reflector having a greater focal length than said refractory reflector.

5. Irradiating device comprising a reflector of refractory material, a quartz lamp near the focus of said refractory reflector and a second reflector formed of two substantially flat portions and arranged to be tilted about a horizontal axis, said refractory reflector being arranged to reflect the rearwardly emitted rays, said second reflector the forwards emitted rays of said lamp, said second reflector having a greater focal length than said refractory reflector.

6. Irradiating device for medical purposes comprising in combination, two plane mirrors converging towards their rear ends, but separated by a gap, two reflecting sections of cylinders of refractory material disposed intermediate said mirrors and separated also by a gap and a quartz lamp tube in the focus of said cylinder sections and extending substantially in parallel with the gap separating them.

In testimony whereof I affix my signature.

FRITZ GIRARD.
